United States Patent Office

Des. 213,832

Patented Apr. 15, 1969

213,832

TELEPHONE DIAL WHEEL OR SIMILAR ARTICLE

David W. Hagelbarger, Morris Township, Morris County, N.J., assignor to Bell Telephone Laboratories, Incorporated, New York, N.Y., a corporation of New York

Original design application Oct. 23, 1965, Ser. No. 87,879, now Patent No. 209,670, dated Dec. 26, 1967. Divided and this application Dec. 21, 1967, Ser. No. 12,195

Term of patent 14 years

Int. Cl. D14—03

U.S. Cl. D26—14

FIG. 1

FIG. 2

FIG. 3

FIG. 1 is a perspective view of a telephone dial wheel or similar article showing my new design;

FIG. 2 is a top plan view thereof; and

FIG. 3 is a side elevation thereof.

The broken lines are shown for illustrative purposes only.

This is a division of design application Serial No. 87,879, filed Oct. 23, 1965 and now design Patent No. 209,670.

I claim:

The ornamental design for a telephone dial wheel or similar article, as shown and described.
